UNITED STATES PATENT OFFICE.

JAMES M. STEPP, OF HUNTINGTON, WEST VIRGINIA.

CLEANING APPARATUS.

Application filed December 30, 1921. Serial No. 526,015.

To all whom it may concern:

Be it known that I, JAMES M. STEPP, a citizen of the United States, and a resident of Huntington, in the county of Cabell and State of West Virginia, have invented certain new and useful Improvements in Cleaning Apparatus, of which the following is a specification.

This invention relates to cleaning devices especially adapted for use in cleaning such floor coverings as carpets and rugs.

Briefly stated the invention forming the subject matter of this application is provided with novel means whereby a cleaning solution or pure water may be supplied in the form of a spray to a floor covering and which upon being applied to the floor covering is picked up by means of a suction head which also picks up the dirt encountered and leaves the rug or carpet as the case may be clean and dry.

A further object is to provide a cleaning device for floor coverings which is of highly simplified construction, durable in use and cheap to manufacture, so that the invention is within the reach of those in limited circumstances.

Other objects and advantages of the invention will be apparent during the course of the following description.

In the accompanying drawings forming a part of this application and in which like numerals are employed to designate like parts throughout the same,

Figure 1 is a perspective of the improved cleaning device in use.

Figure 2 is a detail vertical sectional view through the same.

Figure 3 is a detailed sectional view through a receiver for the dirt, and the cleaning solution carrying the dirt.

Figure 4 is a fragmentary perspective illustrating a slightly modified form of suction creating means.

In the drawing the numeral 5 generally designates a handle to which a container 6 of any desired formation is connected by means of attaching straps 7 and 8. As illustrated in Figure 1 and in detail in Figure 2 the container 6 is supported in an inverted condition and is provided with a cap 10 from which a liquid discharge pipe 11 extends. The forward portion of the liquid discharge pipe 11 is connected to a spray pipe 12 by means of a flexible hose 13, the said spray pipe 12 being arranged rear-

wardly of and supported by a pick up head 14. With reference to Figure 2 it will be seen that the spray pipe 12 which is provided with a plurality of radial discharge openings 60 is secured to the rear side of the pick up head by means of fastening devices 13 of any suitable type. The lower side of the spray pipe 12 is spaced above the lower end of the pick up head 14 and discharges 65 the cleaning or rinsing fluid onto the carpet or floor covering rearwardly of the pick up head. The spray pipe 12 which is perforated throughout its length is of substantially the same length as the pick up head 14 so 70 that the liquid discharged forms a spray of substantially the same length as the mouth of the pick up head. It will be seen that the forward end 15 of the pick up head 14 is extended below the rear edge of the pick up head so that the rear edge of the pick up head is spaced upwardly from the carpet. This permits the loosened dirt and the cleaning solution to be drawn into the pick up head by the suction. 80

A suction tube 20 is connected to the rear end of the head 14 and is provided at its intermediate portion with an outlet opening 21 which communicates with a flexible hose 22. The flexible hose 22 forms a conducting 85 means for the air, dirt and cleaning solution drawn upwardly by the pick up head 14 and the hose or flexible conductor 22 is connected to the cover or cap 25 of a dirt and liquid receiver 26 which may be of glass or 90 other suitable material.

A suction is created within the receiver 26 by means of a vacuum cleaner 27, the frame of which is connected to the receiver by means of a vacuum pipe 28. When the suction cleaner is in operation, a vacuum is 95 created within the receiver 26 and draws air through the vacuum tubes 22 and 20 and in through the pick up head 14.

When the vacuum is created within the 100 pick up head 14 the cleaning solution which has been previously sprayed upon the floor covering and the dirt loosened by the cleaning solution is drawn inwardly through the pick up head. This leaves the floor covering 105 clean and dry and due to the fact that the liquid cleaning solution is not allowed to remain on the covering for a long period, the solution is not allowed to penetrate.

The discharge of the cleaning solution is 110 controlled by means of a valve 30 having a throttle arm 31 connected to the control rod,

the said control rod having its rear portion connected with a loop 33 adapted for the reception of one of the fingers of the operator. The rod 32 is passed through a guide 5 sleeve 34 carried by a handle 35 extended into the rear portion of the suction tube and held therein by means of a fastening device 37.

In the modified form of the invention illustrated in Figure 4 an electric motor 40 is mounted upon a platform 41 and the said motor operates a suction fan enclosed within a casing 42. The suction fan is connected by means of the pipe 44 to the liquid and dirt receiving member of the outfit.

In operation the handle 35 is operated for drawing the pick up head over the surface of the floor covering and the valve 30 is simultaneously actuated for permitting the cleaning solution to be discharged through the spray pipe. The cleaning solution discharged from the spray pipe spreads upon the floor covering rearwardly of the head 14 and the suction created within the head 25 picks up the dirt and the cleaning solution so that the floor covering is left dry and

clean and with a very desirable lustre. The apparatus may be operated entirely by one person and is extremely economical in operation. Furthermore the several parts may be economically manufactured so that the entire apparatus may be sold at a reasonable price. Various changes may be made in the various parts of the apparatus or if desired the apparatus may be left perfectly plain.

Having thus described the invention, what is claimed is:—

A cleaning apparatus for floor coverings comprising a pick-up head having a narrow elongated mouth, a handle for said head, a container for a liquid cleaning solution carried by said handle and having a discharge pipe, a spray pipe connected to said discharge pipe and carried by said head in spaced parallel relation to said narrow elongated mouth, the side of said mouth adjacent said spray pipe being spaced from the floor covering whereby the dirt and the liquid cleaning solution may readily enter the head.

JAMES M. STEPP.
